UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

WIRELESS RECEPTACLE.

1,253,873.

Specification of Letters Patent. Patented Jan. 15, 1918.

Application filed July 24, 1913. Serial No. 780,985.

To all whom it may concern:

Be it known that I, HENRY T. PAISTE, a citizen of the United States, residing in Philadelphia, Pennsylvania, have invented

5 certain Improvements in Wireless Receptacles, of which the following is a specification.

One object of my invention is to provide a novel form of lamp or plug receptacle 10 which in addition to being of relatively simple and substantial construction, shall have the connections between its various terminals made of permanently mounted strip metal pieces to the exclusion of wires.

15 I also desire to provide a receptacle, whose contact members and terminals shall be identical in construction and so arranged that the structure as a whole is bi-laterally symmetrical.

20 Another object of the invention is to provide a receptacle having a contact carrying member provided with terminals for attachment to a pair of current supply mains or conductors and of such design that 25 it may be used in connection with any of several different forms of receptacle bodies, the construction being such that said contact carrying member may be conveniently adapted to receive either a contact plug or 30 a lamp.

These objects and other advantageous ends I secure as hereinafter set forth, reference being had to the accompanying drawings, in which:

35 Figures 1 and 2 are respectively a side elevation and a plan of a portion of a conduit illustrating one form of my invention applied thereto;

40 Fig. 3 is an inverted perspective of one form of receptacle member forming part of my invention;

Fig. 4 is a perspective view of the contact carrying member;

45 Fig. 5 is an inverted perspective view of an adapter member which may be used with the contact carrying member shown in Fig. 4;

Fig. 6 is a longitudinal section on the line a—a Fig. 2:

50 Fig. 7 is a transverse section of the receptacle member shown in Figs. 1, 2 and 3;

Fig. 8 is a transverse section of a conduit illustrating the contact carrying and adapter members mounted thereon;

Fig. 9 is a side elevation partly in section 55 of the adapter and contact carrying members shown in Figs. 4 and 5;

Fig. 10 is a plan of the contact member shown in Fig. 4;

Fig. 11 is a plan of a slightly modified 60 form of my invention;

Fig. 12 is a plan similar to Fig. 11 but with the adapter member removed;

Fig. 13 is an inverted plan of the adapter member used with the apparatus shown in 65 Fig. 11; and

Fig. 14 is a side elevation of the structure shown in Fig. 11.

In the above drawings 1 represents a portion of a metal conduit which has the form 70 of a tubular structure internally threaded at its ends as indicated at 2 in Fig. 6, for the reception of the correspondingly threaded ends of metallic pipes designed to carry electrical conductors. One side of 75 this conduit is provided with an elongated rectangular opening designed to receive a contact carrying member 3, (Figs. 4 and 10), it being noted that the facial edges of this opening are plane and designed to receive 80 the plane edges of the adapter or receptacle members 4 and 5, as may be desired. The contact carrying member 3 consists of a casting of insulating material having a body part 6 substantially rectangular 85 in plan as shown in Fig. 10 and longitudinally elongated ends 7, so that when introduced into the conduit 1, as shown in Fig. 6, it with said ends forms in effect, a longitudinal partition therein, which receives a 90 pair of current conductors on its opposite sides.

On each of these ends 7 is a head 8 overhung so as to rest upon the inwardly projecting flanges of the opening in the conduit 1 and notched at 9 to permit of the passage of a holding screw 10. Between the ends 7 and the heads 8 thereof is a recess within which are mounted two similarly formed spring contacts 11 and 12 of resilient 100 strip metal. Each of these consists of a predetermined length of material having one end bent at right angles to its body to form a clamping member 13 and having its opposite end bent over through an angle of 105 somewhat less than 180°, the arrangement being such that their main or body portions extend immediately adjacent the vertical

ends of the recess between the heads 8 with their free, bent over ends projecting toward each other.

The upper face of the body 6 is divided into two similar parts by a diagonal rib or partition 14 and on opposite sides of this are mounted terminal pieces 15 and 16 each having a holding screw 17. The outer extremity of each of said terminal pieces is 10 bent or curved parallel to and adjacent one side of the head of its screw so as to confine thereunder, the wire constituting the electrical conductor which extends through the conduit 1. As shown in Figs. 4 and 8, 15 the opposite sides of the body 6 have their top portions somewhat concaved for the reception of these extremities of the terminal pieces and for the reception and support of the current conducting wires or 20 mains which as before indicated, run over said body portions along opposite sides of the ends 7. The terminal piece 15 is electrically connected to the contact piece 12 by a screw 18 extending upwardly through the 25 body 6 of the contact carrying member 3 and having its head counter-sunk in a suitable cavity in the under side thereof. Similarly the terminal piece 16 is electrically connected to the contact piece 11 by a second 30 screw 19. It is noted that the two contact members 11 and 12 have their tops substantially flush with the top faces of the heads 8 of the body of the contact carrying member and their adjacent faces are each provided with a pressed out projection or lug 35 20 for a purpose hereafter noted.

If it should be desired to use a lamp or attachment plug receptacle in connection with the conduit and contact carrying member, I may employ a combination of parts such as is illustrated in Figs. 3 and 7. Such a member 5 preferably consists of a hollow substantially rectangular base piece 21, designed to fit upon the face of the opening in the 40 conduit 1 to which it is held by the screws 10. The upper face of this member has a cylindrical extension 22 in which is mounted a threaded metallic shell 23 forming one of the terminals of the receptacle. As shown 45 in Fig. 7, said shell is provided at its inner end with inwardly projecting portions 24 electrically connected by screws 25 with a curved metallic plate 26 set in a suitable recess in the under face of a transverse partition 27 formed integral with and extending across the hollow base 21 of the receptacle member. This plate 26 has an integral extension 28 lying at right angles to its plane against one face of the partition 27, there 50 being a cavity or depression 29 in this extension, designed to receive the projection 20 of one of the contact pieces 11 or 12 belonging to the contact member.

The opposite vertical side of the partition 55 27 has a contact plate 30 whose lower end 31

is bent at right angles within a slight recess or depression in the under face of said partition, being electrically connected to a central spring contact 32 at the bottom of the cavity of the cylindrical extension 22 by a screw 33 (Fig. 7). This contact 32 preferably consists of a strip of metal having in one end a hole for the reception of the screw 33 and bent at its middle point through an angle of substantially 180°, so that its free end extends over its opposite end as shown in Fig. 6, although spaced away from the same.

The plate 30 has a depression or recess (Fig. 6) for the reception of one of the projections 20 of the spring contact 12, for example, and under conditions of use the receptacle member would be mounted on the conduit 1 with its partition 27 extending between the two contact members 11 and 12 of 85 the contact carrying member, so that said contacts would electrically engage the parts 28 and 30, and would thus be in electrical connection with the shell 23 and the central contact 32. As shown in Fig. 6 the screws 90 10 rigidly and removably connect the contact carrying member to the conduit.

Should it be desired to utilize the contact carrying member, with or without the conduit, for the reception of a contact plug 34, Fig. 8, the receptacle member would be replaced by the adapter member shown in Fig. 5. This latter consists of a hollow, substantially rectangular base piece 21, which instead of the cylindrical extension 22, has a plane upper face with a central rectangular perforation 35. The interior of this base is similar to that of the receptacle member except that its end partition 27 is omitted to permit of the passage of a central projection 36 from the insulating body 34 of the contact plug, which on two of its opposite faces is provided with a pair of contact plates 37 and 38. 100

The dimensions of this projection 36 and of said plates are such that when the adapter member 4 is mounted over the contact carrying member 3, the heads 8 of the latter fit within the recesses 39 and 40 at the ends of said adapter member and the contact plates 37 and 38 of the contact plug 34 fit between and electrically engage the spring contacts 11 and 12, with the projections 20 of said contacts fitting into the openings 41 of said plates, as described and claimed in my application for patent on an attachment plug, filed of even date herewith, Serial Number 780,986. The contact plates 37 and 38 are electrically connected to the two conductors of a cable 42 which enters the contact plug 34. 115 120 125

Under operating conditions a pair of current carrying conductors in the conduit 1 extend on opposite sides of the relatively narrow body of the contact carrying mem- 130

ber and properly bared portions are led over the extremities of the terminal pieces 15 and 16, after which the screws 17 are set up so as to insure perfect electrical contact.

5 Current from said terminal pieces is then free to flow to the contact pieces 11 and 12 respectively and thence to the terminals 23 and 32 of the receptacle member or to the contact plates 37 and 38 of the contact plug 10 34 as the case may be.

In that form of my invention shown in Figs. 11 to 14 inclusive, I have illustrated the contact carrying member as adapted to fit into a wall box or cabinet, and for the 15 purpose of attaching it to the cover plate of such structure, it is provided with a pair of perforated metal lugs or plates 43 at its opposite ends. In this instance as before, its body is formed of a casting 3* having 20 heads 8* between which is a recess for the reception of two similar spring contacts 11* and 12*. In this instance, however, said contacts are integral with the terminal plates 15* and 16* which lie in recesses at the 25 opposite sides of the body 6* and adjacent vertically extending channels 45 through which conductors may be extended for engagement with the holding screws 17.

This form of receptacle is particularly 30 adapted for use in connection with a contact plug such as is shown in Figs. 8 and 9 and for the purpose of adapting it to this device, I provide a substantially cylindrical casting 46 shaped to fit between the 35 heads 8* of the contact carrying member and of such length as to be substantially flush with their top faces. This casting is provided with a central passage of substantially rectangular section designed to 40 receive the projection 36 with the contact plates 37 and 38 of the contact plug 34, so that when said casting is in place as illustrated in Fig. 11, the said contact plates electrically engage the two spring contacts 45 11* and 12*.

In any case it will be noted that the receptacle is of a relatively simple construction and while being designed for engagement with the main current carrying conductors of the circuit, employs strips or 50 spring bars throughout for transmitting the current between its terminals. It will moreover be noted that the device, in addition to being simple, is substantial and has its 55 parts so arranged that the danger of short circuiting is reduced to a minimum.

I claim:—

1. A wireless receptacle consisting of an insulating casting including a relatively 60 narrow body having upwardly extending end portions spaced apart to form a recess and including lateral extensions; with two conducting members of similar construction consisting of U-shaped spring contact 65 portions in the recess respectively adjacent

end portions of the casting and laterally projecting terminal portions on the outside surface of the body extensions for the attachment of conductors.

2. A wireless receptacle consisting of a 70 relatively narrow insulating casting having two upwardly projecting ends spaced apart to form a recess; a rib extending diagonally across said recess; and two similar conducting members having contact portions respectively mounted in opposite portions of the recess on opposite sides of the rib and provided with terminal portions projecting respectively on opposite sides of said casting.

3. A wireless receptacle consisting of an 75 elongated insulating body having upwardly projecting headed end portions spaced apart to form a recess and provided with lateral extensions between and below the top surfaces of said end portions; with two similar conducting members having spring contacts respectively mounted in opposite parts of the recess adjacent the ends of the body and also provided with laterally projecting terminal portions respectively projecting over the side extensions of the casting, the body being cut away on each side under said end portions to provide channels leading to the terminal portions.

4. The combination of a conduit for electric conductors having a side opening; with a receptacle mounted in the opening so as to extend into the conduit, said receptacle consisting of a relatively narrow body longitudinally dividing the conduit into two parts; and conducting members mounted on said body including oppositely disposed contact portions lying in two parallel planes and terminal portions respectively mounted 105 within the two parts of the conduit.

5. The combination of a conduit for electric conductors having a side opening; a receptacle mounted in said opening and including a relatively narrow body extending 110 into the conduit so as to divide it longitudinally into two chambers, there being lateral projections extending from opposite sides of the body into said chambers; two conducting members having contact portions respectively opposite each other; and terminal portions projecting laterally upon the lateral extensions of the body within the two chambers of the conduit.

6. The combination of a conduit for electric conductors having a side opening; a receptacle consisting of a relatively narrow insulating body dividing the conduit longitudinally into chambers and having headed end extensions engaging the edges of the 125 conduit opening, said body having a recess between its ends and being formed with portions extending laterally into the conduit; with conducting members of similar construction having spring contacts re- 130

spectively mounted in opposite portions of the recess of the body; and terminal portions extending over the lateral projections of the body respectively within the chambers in the conduit.

7. The combination of an insulating body; two oppositely disposed contacts thereon; terminal portions for the contacts respectively extending at opposite sides of the body; and a member consisting of an insulating base having a hollow cylindrical projection; two oppositely disposed contact plates mounted on the base in positions to respectively engage said contacts; and terminal members in said cylindrical extension respectively connected to said contact plates.

8. The combination of a conduit for electrical conductors having a side opening; a member mounted over said opening and consisting of an insulating base having a hollow cylindrical extension; terminals in said hol-

low extension for engagement with the terminals of an electroreceptive device; two contact plates mounted inside the insulating base and respectively in electrical connection with said terminals; a body of insulating material between the insulating base and the conduit extending into the latter; two spring contact members mounted on said body and in separable engagement with the contact plates of the insulating base; with terminal pieces respectively connected to said spring contacts and projecting on opposite sides of the body within the conduit.

In testimony whereof, I have signed my name to this specification, in the presence of two subscribing witnesses.

HENRY T. PAISTE.
